UNITED STATES PATENT OFFICE.

RUDOLPH LIEBMANN, OF NEW YORK, N. Y.

DESIGN FOR A CAMPAIGN-BUTTON.

SPECIFICATION forming part of Design No. 21,729, dated July 19, 1892.

Application filed May 31, 1892. Serial No. 435,078. Term of patent 3½ years.

To all whom it may concern:

Be it known that I, RUDOLPH LIEBMANN, a citizen of the United States, and a resident of New York, in the county and State of New York, have invented and produced a new and original Design for Campaign-Buttons, of which the following is a specification, reference being had to the accompanying drawing, forming part of this specification.

10 The drawing represents a face view of the head of a button or badge embodying my new design, the same being drawn on an enlarged scale.

15 In the drawing the letter A designates the head of the button, the greater portion of which is occupied by a central field a, representing the Western Hemisphere. About centrally within this field are arranged two crossed flags b and c, the one b being a repre-

sentation of the United States flag and the 20 other c the flag of a foreign nation. At the lower left hand of the field is the representation of a factory d, while below the flags is shown a disk or shield e. The central field is encircled by a flat marginal border f, as 25 shown.

What I claim as my invention is—

The design for a campaign button, substantially as herein shown and described.

In testimony that I claim the foregoing as 30 my invention I have signed my name, in presence of two witnesses, this 28th day of May, 1892.

RUDOLPH LIEBMANN.

Witnesses:

KLAS H. TERUSTEDT,
J. J. MALLE.
